SILAS G. RANDALL, OF PROVIDENCE, RHODE ISLAND.

Letters Patent No. 96,265, dated October 26, 1869.

IMPROVEMENT IN PNEUMATIC DIAPHRAGM WATER-ELEVATORS.

The Schedule referred to in these Letters Patent and making part of the same.

To all whom it may concern:

Be it known that I, SILAS G. RANDALL, of the city and county of Providence, and State of Rhode Island, have invented a certain new and useful Method of Elevating Water by Pneumatic Pressure; and I do hereby declare the following specification, taken in connection with the drawings furnished, and forming a part of the same, to be a true, clear, and exact description thereof.

The nature of my invention consists in the employment of automatic mechanism, operated by pneumatic pressure, for the purpose of effecting and maintaining, when desired, a continuous flow of water raised from wells, cisterns, or other sources of supply.

Reference being had to the drawings—

Figure 1 represents, in vertical section, the entire apparatus.

a represents an air-pump, of ordinary construction.
b is a pipe, leading from the base of the pump.

E is an air-tight vessel, and is placed at the bottom of or submerged in a well or cistern. It is connected with the pump *a* by means of the pipe *b*.

This air-tight vessel is divided into three compartments, one upper and two lower.

The upper chamber, marked *g*, is an air-chamber, so called, from which the discharge-pipe *d* conducts water upward to delivery.

The lower portion of the vessel is separated into two compartments, by a flexible diaphragm of vulcanized rubber, or other suitable material, moulded in a pan-shaped form, the edges of which are tightly secured to the sides, top, and bottom of the chamber in any obviously practical manner.

The compartment on the right of the diaphragm is called the water-chamber, into which water is drawn from the well through spring-valve *K*, and from which it is discharged to the air-chamber *g*, through valve *j*.

The compartment on the left of the diaphragm is called the operating or compressing-chamber, and contains the operative mechanism for producing the desired end. This chamber communicates with the air-pump *a*, by means of the pipe *b*, through which air is forced for operating the mechanism.

A pipe, *c*, also communicates with the interior of this chamber, its upper end being always open.

It will be observed that the pipes *b* and *c*, at point of entrance to the chamber, are closely adjacent to each other, and are both opened and closed alternately by one valve, marked *l*. This valve is in the form of a flat plate, vibrating laterally upon a pin or stud, secured to the under side of the top of the chamber, so that when one end of the valve is moved to the right or left, the other end is in relation with the pipes *c* or *b*, as the case may be. The other end of the plate forming the valve is fork-shaped, with shoulders at

the edges, projecting downward. Between these two forked arms is a stud, projecting downward a straight flat edge, and is secured firmly to the top of the chamber.

It will be remembered that the diaphragm *i* constitutes the partition-wall between the water-chamber and the operating or compressing-chamber. This diaphragm is moulded in such a form that its natural tendency is to project its bowl or pan-shaped form into the compression-chamber, and is only capable of being reversed by pressure, upon the removal of which it resumes its natural position.

To the centre of the diaphragm, in the compression-chamber, is connected a rod, which in turn is connected to a lever, *m*, secured to the side of the chamber by a stud-fulcrum.

The upper end of this lever *m* is composed of a flat, straight spring, which, when the lever is vertical, is in contact with the stud before described as between the forked arms of the valve *l*.

In the drawing, the sides of the well or cistern are marked *f*.

It is obvious that the depth of the well, or its distance from the air-pump, affects in no way the principle involved, and herein exhibited.

Figure 2 represents the same as in fig. 1, but exhibits the diaphragm *i* inverted, it having been projected into the water-chamber.

Figure 3 represents the water and compression-chamber in cross-section, and exhibits more clearly the valve *K*.

Corresponding parts are lettered alike in all the figures.

The operation is as follows:

By way of illustration, we will presume the diaphragm *i* to be projecting into the compression-chamber, as shown in fig. 1. The air-pump being put into operation, air would be forced by way of pipe *b* into the chamber. The valve *l* being in position closing the pipe *c*, would prevent the escape of the air. As the pressure increased, the diaphragm *i* would be forced outward, carrying with it the lower end of the lever *m*, causing its upper or spring-end to bear strongly against the stud in the top of the chamber, between the forked arms of the valve *l*. As this spring is bent, it is obvious that when at a certain point it would slip over the stud, and by striking sharply against the downward-projecting shoulders of the forked-shaped valve-arm, produce an instantaneous movement of the valve *l*, thereby closing the pipe *b* and opening the pipe *c*. By this change in the position of the valve, the air is permitted to rapidly escape, causing the diaphragm *i* to resume its former position, the lever *m* in the movement having struck the stud, and the valve-arm again closing the outlet *c* and open-

ing the inlet *b*, and a new or repeated movement commences.

The effect of this automatic movement, meantime, in the water-chamber, has been as follows:

By the inward pressure of the diaphragm against the body of water in the chamber, it has been forced upward, through spring-valve *j*, into the air-chamber *g*, thence to delivery by pipe *d*. Upon the return of the diaphragm to its natural position, the spring-valve *K* (which of course should be provided with suitable strainers) opens inwardly, and thereby admits water from the well into the chamber. When the diaphragm again advances, the valve closes.

Although the movement of the operative parts is very rapid, yet, from the great comparative capacity of the valve *K*, it secures an ample charge of water.

The chambers being capable of construction upon a small scale, will admit of the application and use of the apparatus in connection with artesian wells, and by having a continuous pressure of air, it would maintain an equally continuous flow of water.

It is evident that the form or shape of the diaphragm may be varied as desired; as, for instance, it could be constructed in the form of a convex disk, or a square, with conical projection; or the same operative principles would be involved in the use of a piston and springs within a cylinder, with similar automatic mechanism, the whole being operated by compressed air, substantially in the manner as described.

I am well aware that automatic mechanism, operated by water under pressure, has been used in a

variety of forms, with greater or less success, under the general name of hydraulic rams and engines; but I am not aware that any apparatus has, before my present invention, been devised, by means of which compressed air is made to operate automatic mechanism for the purpose of elevating water. A pneumatic apparatus must essentially differ from one operated by hydraulics.

One of the most important uses to which my invention can be applied is that of freeing deep mines of water, and supplying at the same time a liberal supply of fresh air, with no greater requisite outlay of motive-power than is now expended in the performance of either operation.

Having thus described my invention, I desire to be distinctly understood that I do not claim the elastic diaphragm, nor the arrangement of the induction and ejection-valves in the water-chamber, as such have been long in use; but

I do claim as new, and for which I desire Letters Patent of the United States—

In a compartment-pump, in which the matter to be forced or elevated is separated from the operative mechanism, the combination of the pipes *b* and *c*, and the alternating valve *l*, connected to and operated by the reciprocating compartment, substantially as shown and described.

SILAS G. RANDALL.
